MEANS FOR INSERTING FILLED ENVELOPES IN CARTONS

Application filed January 14, 1932. Serial No. 586,534.

The present invention relates to means for inserting a coloring envelope in a carton and more particularly to the insertion of envelopes containing coloring matter in packages of oleomargarine.

It is desirable that packages of oleomargarine be sold at retail with the coloring matter contained in separate closures so that the housewife may color the oleomargarine at home.

There are various ways of selling such coloring matter, such for instance as in capsules.

The present invention concerns itself with the equipment of package of oleomargarine with an envelope containing the proper coloring matter, which envelope is inserted in the package and is available for use when the package is opened.

An object of the present invention is to provide means applicable to an oleomargarine packaging machine for inserting envelopes of coloring matter in every package or carton of oleomargarine packaged by such machine.

Another object of the invention is to provide the provision of means whereby a plurality of envelopes of coloring matter may be conveniently maintained adjacent the packaging machine and delivered one by one to the packages as the same are completed in the packaging machine to the end that every package or carton may be supplied with an envelope of coloring matter.

A further object of the invention resides in the provision of means for so timing the closing of the package and the delivery of the envelope containing the coloring matter as not to impede the output of the packaging machine.

The above, other and further objects of the invention will be apparent from the following description, accompanying drawings and appended claims.

Generally speaking, the invention contemplates mechanism which may be applied to a packaging machine, which mechanism is of such character as to carry a plurality of envelopes of coloring matter which may be

withdrawn one by one and delivered by gravity into an oleomargarine package.

An exemplification of the mechanism embodying principles of the present invention is illustrated in the accompanying drawings, 55 and the views thereof are as follows:

Figure 1 is a fragmental top plan view of an oleomargarine packaging machine showing applied thereto the mechanism for supplying envelopes of coloring matter to the 60 packages, which mechanism embodies principles of the present invention.

Figure 2 is an enlarged fragmental elevational view of a part of the packaging machine and showing the relative position of the 65 envelope supply and delivery mechanism with respect to the packaging machine parts.

Figure 3 is a fragmental top plan view, partially in section, of the box for supply of envelopes of coloring matter and illustrating 70 suction means for withdrawing the envelopes one by one from such box.

Figure 4 is a vertical sectional view taken substantially in the plane of line IV—IV of Figure 2.

Figure 5 is an end view of an oleomargarine carton in closed position, showing in dotted lines the contained envelope of coloring matter.

Figure 6 is a fragmental vertical sectional 80 view through a portion of the envelope supply box, through the guide means and a portion of the suction withdrawal means, showing the latter in full lines in outward position and in dotted lines in inward position in engagement with the endmost envelope in the box.

Figure 7 is a side elevational view, partially in section and with parts broken away, of an oleomargarine package showing the 90 contained coloring matter envelope enclosed within it.

The drawings will now be explained.

Only so much of the packaging machine is illustrated as is thought necessary for 95 complete understanding of the present invention.

Figure 1 illustrates a fragmental portion of a packaging machine suitable for packaging bricks of oleomargarine or similar sub- 100

stances and illustrates a row of bricks 1 of oleomargarine which are advanced along a trackway 2 by suitable means. A pile of wrappers for the bricks is supported on a 5 table which wrappers are fed one by one under the individual blocks 1 as the same are delivered to the table. There is an opening in the table underneath the plunger 5 over which opening the operator places one 10 of the wrappers as the endmost brick 1 is delivered over the same. The plunger 5 thereupon moves the bricks of oleomargarine on the wrapper downwardly onto a conveyor 6 where the oleomargarine is suitably wrapped 15 by proper mechanism.

A carton blank represented generally at A is fed onto a shelf or table 7 in open position. A substantially circular hook member 8 is carried on a plunger 9, which is reciprocated by any suitable mechanism as a part 20 of the packaging machine. The hook 8 is advanced where it engages the outermost panel 10 of the blank A and then as the plunger is moved to the left as viewed in 25 Figures 1 and 2, the blank is rolled into box-like form as shown in Figure 2, leaving the endmost panel 11 and its end tabs flat. The blank A is made with five panels so that when 30 the blank has been rolled into substantially box-like form as viewed in Figure 2, the fifth panel 11 will remain flat for the reception of the coloring matter envelope as later described.

The coloring matter inserting mechanism 35 embodying principles of the present invention includes a box 12 which is disposed above the shelf or table 7. The box 12 is provided with a follower 13 acting against a supply of filled coloring matter envelopes 14 to 40 urge these envelopes towards the delivery end of the box, which, in the drawings, is illustrated at the right.

Guide means for receiving an envelope from the box 12 are provided at the discharge end of the box and in the present instance, such guide means comprise a box-like member 15 fastened against the discharge end of the box 12 and with a depending chute portion 16 leading downwardly and stopping 50 short of the shelf or table 7. The box 12 and the guide means 15 are so positioned with respect to the shelf 7 and the carton blanks thereon as to discharge a coloring matter envelope 14 onto the end tab 43 of the panel 55 11 of the blank. The chute 16 is reduced toward its lower end so as to discharge the envelope vertically, while the guide means is enlarged at its upper end to more readily receive an envelope withdrawn from the 60 box 12.

Means are provided in the guide means for stopping passage of an envelope along the same in order to insure proper and timed delivery of an envelope onto the blank A ready 65 for enfolding within the blank when the same

is closed by the final operation of the packaging machine.

Such means are herein illustrated as comprising a stop member 17 which is reciprocably projected through the lower part of the chute 16. The stop member 17 is carried on the end of a reciprocable rod 18 mounted in suitable bearings 19 and 20 in the frame structure, that is, in the uprights for carrying the box 2. A collar 21 is secured to the 70 rod 18 by a set screw 22 for limiting movement of the rod for stopping passage through the chute 16, that is, for movement to the 75 right as viewed in the drawings.

Another collar 23 is secured to the rod 18 80 near the bearing 20 and between the collar 23 and the bearing 20 a spring 24 surrounds the rod, the tendency of which is to move the rod to stopping position, that is, to the right as viewed in the drawings.

A bracket 25 is suitably secured to the rod 18, which bracket has pivoted thereto at 26 a dog 27 which is normally retained in operative position by a spring 28.

The plunger 9 is provided with a bracket 29 which carries a finger 30 pivoted in the bracket at 31 and maintained in operative position by the action of a spring 32 acting against the finger 30 which normally maintains the finger against the stop pin 33. The spring 32 is of sufficient strength so that when the finger 30 engages the dog 27 on the rod 18 movement of the rod 18 to the left against the action of the spring 24 may take place for a limited amount of movement. When the rod 18 has been moved to the left by movement of the plunger 9 to the left a sufficient distance, the compression of the spring 24 overcomes the springs of the spring 32, whereupon the finger 30 moves away from the dog 27 thus freeing the dog from engagement by the finger whereupon the rod 18 is moved to the right with snap action by the spring 24, that is, the stop member 17 is returned to stopping position.

The illustrated means for withdrawing an envelope 14 from the box 12 consists of suction means and includes a suction nozzle 34 attached to the end of a suction pipe 35 carried on a reciprocating pipe 36, which pipe in turn is given reciprocable movement by mechanism to be later explained.

A chamber 37 is connected by means of pipe 38 to a suitable source of suction. The chamber 37 has an outlet 39 opening into the path of movement of the movable pipe 36. The pipe 36 has an opening 40 for purposes to be later explained.

The pipe 36 and the attendance suction nozzle 34 is given reciprocable movement by means of a rod 41, mounted in brackets 42 attached to the side of the box 12, by a lever 43 which is connected to part of the packaging machine mechanism having reciprocable movement, such as illustrated in Figure 1.

The lever 43 is provided with spaced ears 44 while the rod 41 is provided with a roller 45 disposed between the ears 44 so that as the lever 43 is given reciprocal action through 5 the instrumentality of the packaging machine the ears 44 will selectively contact the roller 45 and impart reciprocal movement to the rod 41 and the attached suction nozzle 34. The ears 44 are spaced a greater distance 10 than the diameter of the roller 45 to provide lost motion for these parts. The lost motion connection just mentioned allows the nozzle 34 to dwell at each end of its stroke, so that proper suction connection may be made 15 with the endmost envelope 14 in the box 2 when the nozzle is moved inwardly and a sufficient length of time may ensue after the nozzle drops the envelope into the chute 16 before return movement of the nozzle commences. 20

The stop 17 is actuated by the packaging machine mechanism in timed relation so that the stop will be moved from stopping position to allow an envelope to drop into the carton 25 in the position illustrated in Figure 2 just prior to the time the carton is lowered for final closing.

After an envelope has been delivered onto the tab 43 of the panel 11 of the blank the 30 packaging machine then lowers the blank to dotted line position of Figure 2, during which time the plunger 44 becomes effective to move the panel 11 against the adjacent side of the box and other mechanism, not shown, moves 35 the tab 43 against the end of the box and tucks in the flap thereof so as to lock the package in closed position. During the time the blank is rolled into the position shown in full lines in Figure 2, and the time it is lowered as just 40 described, the opposite end has been closed by suitable mechanism and the near end has been closed all except as to the flap 43 on the panel 11 so that the envelope of coloring matter is inserted or delivered to the box immediately 45 prior to final closing of the same, that is, immediately prior to the closing of the final end flap. After the carton has been closed in the manner described, it is moved by suitable mechanism to a convenient place for storage 50 or for packing in cases or crates.

The operation of the mechanism of the present invention is as follows:

The full line positions shown in Figures 1 and 2 are the positions assumed by the parts 55 after an envelope 14 has been withdrawn from the box 12 and delivered to the chute and passed the stop 17. The envelope is indicated at 14 in Figure 2 with an edge lying against the end tab 43 of the panel 11.

As the carton descends for the final closure, the plunger 9 moves to the right to engage another blank to roll it into the position of Figure 2. On the return movement of the mechanism, the rod 41 is moved by the lever 60 43 so that the suction cup or nozzle is brought

against the endmost envelope 14 in the box 12, which movement brings the port 40 in the pipe 36 in register with the port 39 in the chamber 37 so that the cup is placed in communication with the source of vacuum whereupon the endmost envelope is picked up by suction in the suction cup 24. As the parts continue the cup then moves to the right until the port 40 is in communication with the air whereupon the suction in the cup is broken and the envelope 14 falls downwardly by gravity through the guiding means 15 against the stop 17. In the meantime, movement to the left of the plunger 9 will bring the finger 30 against the dog 27 and move the stop 17 out of stopping position so that the envelope 70 may fall in the position shown in Figure 2, that is, the position against the tab 43 of the panel 11, whereupon said envelope will be 75 closed within the package or carton by the closing of the end tab 43.

The utilization of an envelope for oleomargarine coloring matter is advantageous in that but little space is required for such envelope when filled with the coloring matter. 80 Figure 7 illustrates an envelope 14 enclosed in the package of oleomargarine and as indicated at 14 in Figure 5.

The invention has been described herein more or less precisely as to details, yet it is to be understood that the invention is not to be limited thereby, as changes may be made in the arrangement and proportion of parts and equivalents may be substituted without departing from the spirit and scope of the invention. 95

The invention is claimed as follows:

1. In a packaging machine of the type wherein a carton blank is folded about its contents and wherein a flap is tucked in position to complete the package, of a support for a supply of inserts, suction means for withdrawing inserts singly from said support, means for guiding an insert toward a carton, means for stopping an insert in its passage through the guide means, means for releasing said stopping means, means for closing a carton by tucking in a flap thereof, said withdrawing and said stopping means being operated in timed relation to the flap closing means so as to deliver an insert into a carton just prior to the closing of the flap. 110

2. In a packaging machine of the type wherein a carton blank is folded about its contents and wherein a flap is tucked in position to complete the package, of means for delivering a filled envelope interiorly of the package prior to closing of the final flap, said means including means for containing a supply of filled envelopes, and guide means adjacent said supply means, means for withdrawing an envelope from said supply means and delivering it into said guide means, said guide means directing the envelope into the package, means for checking passage of an 115 120 125 130

envelope along said guide means, and means operable by the package closing means for releasing said checking means whereby said envelope is free to drop into said package.

- 5 3. In a packaging machine, in combination, a trough adapted to receive a supply of filled envelopes arranged substantially vertically in edgewise stacked relation, means for withdrawing an envelope in vertical position from said trough, guide means for receiving a withdrawn envelope and maintaining the envelope in edgewise position and delivering it in such position into a package, means for stopping passage of an envelope through said 10 guide means at an intermediate point, and means for withdrawing said stopping means to permit completion of movement of said envelope through said guide means and into a package.
- 15 4. In a packaging machine of the type wherein a carton blank is folded about its contents and wherein a flap is tucked in position to complete the package, of means for delivering a filled envelope interiorly of the package prior to the closing of the final flap, said means including means for containing a supply of filled envelopes disposed in edgewise position, guide means adjacent said supply means for receiving an envelope, 20 means for withdrawing an envelope in edgewise position from said supply means and delivering it into said guide means in edgewise position, said guide means directing the envelope into a package in edgewise position, 25 means for checking passage of an envelope along said guide means, and means operable by the package closing means for releasing said checking means whereby said envelope is free to drop into said package.
- 30 5. In combination with a packaging machine, of a support for a supply of filled envelopes, means for withdrawing the envelopes singly from said support in vertical edgewise position, gravitational guide means disposed 35 to receive an envelope from said first means and maintain the envelope in vertical edgewise position, means for arresting movement of an envelope through said guide means, and means for releasing the arrested envelopes 40 whereby the same is free to fall by gravity into a package, the guide means being effective to maintain said envelope in vertical edgewise position after its release from arrest and during its descent into a package.
- 45 55 In testimony whereof, we have hereunto subscribed our names at Chicago, Cook County, Illinois.
